UNITED STATES PATENT OFFICE.

JOHN C. DUEBER, OF CANTON, OHIO.

DESIGN FOR A WATCH-CASE.

SPECIFICATION forming part of Design No. 21,295, dated January 12, 1892.

Application filed November 16, 1891. Serial No. 412,090. Term of patent 14 years.

To all whom it may concern:

Be it known that I, JOHN C. DUEBER, a citizen of the United States, and a resident of Canton, county of Stark, State of Ohio, have 5 invented a new and useful Design for Watch-Cases, of which the following is a full, clear, and exact description, reference being had to the accompanying drawings, making part of this specification.

10 This invention relates to a new design for watch-cases, as shown on a case of bassine form.

Figure 1 is a view in perspective of a watch-case, showing my design. Fig. 2 is a similar 15 view of the edge of the case.

On the front and back lids and central to the case is shown a plain circular portion A, designating the center or poles of the case, from which a series of alternating grooves B 20 and oval ribs C radiate, the grooves diverging as they approach the contour of the lids and the ribs enlarging diametrically, as shown. About the periphery of the lids is shown an

ornamented band E, the edge or margin F of the case between the bands E being covered 25 with a design.

The leading features of the design are the ornamental bands E, the ribbed or fluted lids, and the vermicelli-scroll covering the edge of the watch-case between the bands E, as 30 shown.

What I claim as new, and desire to secure by Letters Patent, is—

The design for watch-cases herein shown and described, the same consisting of the ornamental bands E, the ribbed or fluted lids, and the vermicelli-scroll covering the edge 35 of the watch-case between the bands E, as set forth.

In testimony whereof I have hereunto set 40 my hand this 10th day of November, A. D. 1891.

JOHN C. DUEBER.
